F. GROSS

TROLLEY GUIDE

Filed Sept. 24, 1923

INVENTOR
Frank Gross

BY

Z. Ledermann
ATTORNEY

UNITED STATES PATENT OFFICE.

FRANK GROSS, OF BROOKLYN, NEW YORK.

TROLLEY GUIDE.

Application filed September 24, 1923. Serial No. 664,430.

To all whom it may concern:

Be it known that I, FRANK GROSS, a citizen of the United States, residing at Brooklyn, in the county of Kings and State of New York, have invented certain new and useful Improvements in Trolley Guides, of which the following is a specification.

The main object of this invention is to provide a trolley pole which prevents the current carrying wire from being inadvertently disengaged from the groove of the trolley pulley.

Another object is to provide means adjacent the trolley pulley whereby the current carrying wire is retained in the groove of the pulley.

These and other objects will become apparent in the description below in which similar characters of reference refer to like-named parts in the drawing.

Referring briefly to the drawing, Figure 1 is a side elevational view of the trolley.

Figure 2 is a sectional elevational view taken on line 2—2 of Figure 1.

Figure 3 is a perspective view of one of the pulley guards.

Referring in detail to the drawing, the numeral 10 indicates a trolley pole having the flanged end 11 of a yoke 12 rigidly secured thereto. The side portions 13 of the yoke are provided with aligned openings in which a spindle 14 is secured. A pulley 15, provided with a peripheral groove 16, is rotatably mounted on the spindle and, as is obvious, rides upon the current carrying wire 17. Ears 18 project upwardly from the sides 13 of the yoke and have vertical slots 19 therein. The sides 13 between the ears 18 are provided with vertical recesses 20, the purpose of which will be more fully hereinafter described.

Side guards are provided with the trolley and comprise longitudinal plates 21 bent angularly at their upper edges 22, the turned-over edge being formed into a sharp corner. The lower edge of the guard plates has recesses 23 which are spaced apart a similar distance as the ears 18 of the yoke sides 13. Pins 24 span the open portions of the recesses 23 and are engaged in the slots 19 of the ears 18. A lug 25 projects from the lower edge of the guard plate 23 intermediate its length and is adapted to en-

gage in the aforesaid recess 20 when the plate 21 is in upright position. 55

As previously stated, this device is designed to prevent the pulley 15 from disengaging from the current carrying wire 17. This fact becomes obvious from Figure 2, when assuming that both plates 21 are in an upright position as shown on the left hand side of the illustration in Figure 2. When these plates are in upright position, the inwardly projecting lips 26 will prevent the wire from jumping out of the groove 16 of the pulley 15, as the gap between the lips 26 is less than the diameter of the wire 17. When it is desired to release the pulley from the wire 17, manipulation of either of the plates 21 will accomplish the purpose. 60 When the lugs 25 of the plates 21 are engaged in the recesses 20, said plates are locked in upright position. In order to disengage the lugs 25 from the recesses 20, the plates 21 are lifted upwardly until the respective lug 25 is disengaged from its recess 20, after which the plates may be rotated about the pins 24. 65

I claim:—

1. A trolley comprising a grooved pulley, 80 a yoke supporting said pulley, ears projecting from the sides of said yoke, the sides of said yoke having a recess between each set of ears, the ears being provided with vertical slots, guard plates, means in said plates engaging the recesses between the ears, and means for permitting rotation of said plates.

2. A trolley comprising a grooved pulley, 90 a yoke supporting said pulley, ears projecting from the sides of said yoke and having slots therein, recesses in the sides of said yoke between adjacent ears, guard plates comprising longitudinal members, said plates having recesses, pins spanning said 95 recesses and being engaged in the slots of said ears, angular lips on said plates projecting above the grooved pulley, said guard plates being rotatable in said slots, and means for retaining the guard plates in 100 vertical position.

3. A trolley comprising a grooved pulley, 105 a yoke supporting said pulley, ears projecting from the sides of said yoke and having slots therein, recesses in the sides of said yoke between adjacent ears, guard plates

comprising longitudinal members, said plates having recesses, pins spanning said recesses and being engaged in the slots of said ears, angular lips on said plates projecting above the grooved pulley, said guard plates being rotatable in said slots, a lug on each guard plate insertable into the recesses

between the ears, said lugs when in said recesses being adapted to retain said guard plates in vertical position.

In testimony whereof I affix my signature.

FRANK GROSS.
